UNITED STATES PATENT OFFICE

OLIVER CORMIER, OF PENACOOK, NEW HAMPSHIRE

BOAT

Application filed February 5, 1931. Serial No. 513,704.

This invention relates to collapsible boats and, among other objects, aims to provide an improved, sectional boat adapted to be easily assembled and dismantled so that the sections may be nested together. The main idea is to provide a simple, relatively cheap, portable boat of this character which is adapted to be carried very easily on an automobile trunk rack.

Other aims and advantages of the invention will appear in the description, when considered in connection with the accompanying drawing, wherein:—

Fig. 1 is a side elevation of a metal boat embodying the invention;

Fig. 2 is a top plan view;

Fig. 3 is a top plan view of a cover for one of the sections;

Fig. 4 is a top plan view of the sections nested together; and

Fig. 5 is a fragmentary sectional view taken on the line 5—5 of Fig. 2.

Referring particularly to the drawing, the improved boat there shown is conveniently made of sheet metal or may be composed of separate cast sections. In this example, it is composed of a front or stem section 10, a mid-section 11, and a rear or stern section 12. The length and width of the mid-section are slightly greater than the length and width of the stern section so that the stern section may be nested within it and the stem section is also adapted to be nested in the stern section.

Each of the sections constitutes an individual, water-tight unit and they are shown as having means to lock them together. In the example shown, the mid-section has end walls 13 and a locking flange 14 providing a groove or channel 15 which projects from each end of the section at the bottom. The stem and stern sections 10 and 12 have end walls 16 adapted to abut the end walls of the mid-section and each presents a lip flange 17 and a groove or channel 18 to interlock with the flange 14 and groove or channel 15 on the mid-section, the construction being such that the end sections may be slid downwardly into locking engagement with the ends of the mid-section.

In Figs. 2, 4 and 5, the upper edges of the two end walls 13 of the mid-section are shown as having horizontal flanges or lips 19 to overlie the upper edges of the end walls 16 after the end sections are slid into locking engagement and swung against the end walls 13. These flanges preferably terminate short of the side walls on the mid-section as best shown in Fig. 2. Thus, the sections cannot be disengaged without first swinging the upper edges of the end walls 16 away from the end walls 13 until they are clear of the flanges 19.

While the interlocked end walls may be held in abutting engagement at their upper edges by means of bolts, clamps or the like, seats 20 having suitably spaced or bifurcated vertical brackets 21 secured to their bottom walls which are utilized for this purpose. These brackets are adapted to straddle the abutting edges of the end walls beyond the opposite ends of the horizontal flanges 19 and bottom walls of the seats preferably rest on said flanges.

To prevent the interlocked sections from being displaced laterally, the mid-section is shown as having short forwardly and rearwardly projecting flanges at the opposite sides to overlap the sides of the front and rear sections.

When it is desired to dismantle the boat, it is only necessary to remove the seats, swing the end sections downwardly and lift them out of their interlocking engagement with the mid-section. The sections may then be nested, as shown in Fig. 4, and the seats placed in one end of the mid-section. To hold them nested, there is shown a suitable metal cover 22 adapted to be bolted or otherwise secured to the top of the mid-section. Herein, the cover and side walls of the mid-section have bolting, perforated ears 23 for this purpose. After the cover is secured in place, the boat may be placed and strapped on an ordinary trunk rack. The mid-section is shaped somewhat like a trunk and may be stood on its large end. In fact, the spare room in the nested sections may be used as a storage space.

From the foregoing description, it will

be seen that the improved sectional boat may be made of relatively thin sheet metal by die stamping or shaping and welding operations. Moreover, the sections may be cast 5 of some light weight metal, such as aluminum. The sections provide separate water-proof compartments, which will prevent the assembled boat from sinking even though one of them is punctured.

10 Obviously, the present invention is not restricted to the particular embodiment thereof herein shown and described.

What I claim is:—

1. A boat comprising a plurality of longitudinal watertight sections; integral interlocking tongue and groove connections on the lower edges of the abutting ends of said sections; and seats having downwardly extending brackets engaging the upper edges 20 of said interlocked ends to hold the sections in interlocked engagement.

2. A boat comprising a plurality of metal sections having abutting end walls; interlocking flanges on the lower edges of the 25 end walls; a flange on the upper edge of one abutting wall overlapping the edge of the other to prevent relative vertical displacement of the sections; side flanges engaging the side walls of the joined sections to prevent relative lateral displacement of the sections; and means to hold the joined sections 20 in interlocked engagement.

3. A boat comprising a plurality of metal sections having abutting end walls; interlocking flanges on the lower edges of the 35 end walls; a flange on the upper edge of one abutting wall overlapping the edge of the other to prevent relative vertical displacement of the sections; side flanges engaging the side walls of the joined sections to prevent relative lateral displacement of the sections; and seats having downwardly extending, spaced brackets straddling the upper 40 edges of the abutting end walls to prevent them from being swung out of interlocking engagement.

4. A boat comprising a metal, water-tight mid-section shaped to resemble an automobile

trunk so that it may be carried on a trunk rack; stem and stern sections of such size and shape as to be nested in said mid-section; interlocking tongues and grooves and side flanges on said sections whereby they may be quickly assembled and disconnected; and a cover adapted to be secured to the mid-section.

5. A boat comprising a plurality of metal sections having end walls; interlocking flanges on the lower edges of the end walls; a flange on the upper edge of one wall overlapping the edge of the other to prevent relative vertical displacement of the sections; side flanges engaging the side walls of the joined sections to prevent relative lateral displacement of the sections; and means to hold the joined sections in interlocked engagement.

6. A boat comprising a plurality of nestable sections, said sections adapted for disposition in end to end abutting relationship when assembled for use, each section including a bottom, side and end walls, said bottom, side walls and certain of the end walls being formed in a manner to provide coacting flanges for detachably securing the sections together.

7. In a boat hull, in combination, a pair of independently watertight sections having operating ends, a marginal inwardly turned inwardly disposed flange on one end of one of said sections, and a marginal reversely formed portion on the cooperating end of the other of said sections removably receiving said flange therein.

8. A boat comprising a plurality of longitudinal watertight sections; integral interlocking inwardly disposed tongue and groove connections on the lower edges of the abutting ends of said sections; and seats having downwardly extending portions engaging the upper edges of said interlocked ends to hold the sections in interlocked engagement.

In testimony, that I claim the foregoing as my own, I have hereto affixed my signature.

OLIVER CORMIER.
